(57) **CLAIM**

The ornamental design for a RV circuit tester, as shown and described.

DESCRIPTION

FIG. 1 is a perspective view of a first embodiment of a RV circuit tester showing my new design;

FIG. 2 is a front elevation view of the first embodiment;

FIG. 3 is a rear elevation view of the first embodiment;

FIG. 4 is a left side elevation view of the first embodiment;

FIG. 5 is a right side elevation view of the first embodiment;

FIG. 6 is a top plan view of the first embodiment;

FIG. 7 is a bottom plan view of the first embodiment;

FIG. 8 is a front and left perspective view of a second embodiment of a RV circuit tester showing my new design;

FIG. 9 is a rear, right and top perspective view of the second embodiment;

FIG. 10 is a front elevation view of the second embodiment;

FIG. 11 is a rear elevation view of the second embodiment;

FIG. 12 is a left side elevation view of the second embodiment;

FIG. 13 is a right side elevation view of the second embodiment;

FIG. 14 is a top plan view of the second embodiment; and,

FIG. 15 is a bottom plan view of the second embodiment.
